A. H. DAVIS

METALLIC TIE AND RAIL FASTENER

Filed Oct. 5, 1923

FIG.1.

FIG.2.

FIG.3.

A. H. Davis
INVENTOR

BY *G. H.arpman*
ATTORNEY

UNITED STATES PATENT OFFICE.

ALBERT H. DAVIS, OF WARREN, OHIO, ASSIGNOR TO E. W. PRICE, OF WARREN, OHIO.

METALLIC TIE AND RAIL FASTENER.

Application filed October 5, 1923. Serial No. 666,728.

To all whom it may concern:

Be it known that I, ALBERT H. DAVIS, a citizen of the United States of America, residing at Warren, in the county of Trumbull 5 and State of Ohio, have invented certain new and useful Improvements in Metallic Ties and Rail Fasteners, of which the following is a specification.

This invention relates to metallic ties and 10 rail fasteners, and the invention has for its primary object to provide a tie for supporting rails which will form a firm foundation or roadbed for a track.

Another object of this invention is the 15 provision of novel means of constructing a metallic tie and rail fastener by using sheet steel and pressing the same into the form desired.

A still further object is to provide a tie 20 having an inverted U-shape body portion in order that the same may be imbedded firmly in gravel, concrete or other suitable binding material in order to support the tie.

With the above and other objects in view, 25 which will more readily appear as the invention is better understood, the same consists in the novel construction, combination and arrangement of parts to be hereinafter more fully described and then specifically 30 pointed out in the appended claim.

Referring to the drawing forming part of 35 this specification, like numerals of reference designate corresponding parts throughout the several views, in which:

Figure 1 is a perspective view of my invention showing manner of connecting and securing rails to a tie.

Figure 2 is a perspective view of my invention showing a tie with a rail secured thereto and rails fastened together and secured to said tie.

Figure 3 is a cross section of Figure 2 taken on line 2—2.

To put the invention into practice, I have 45 provided an inverted U-shape tie member 1. This tie member 1 is formed of sheet metal, or the like, and also provided with an opening 2 for the reception of a base portion 3 of a rail 4.

By referring to Figure 1 it will be seen 50 that I have provided a recess 5 into which is placed an outer flange 6 of the base por-

tion 3 of the rail 4. It will be seen that this recess 5 is formed with a flange 7 forming the upper portion of the recess 5, which fits 55 over the upper surface of the outer flange 6. After the rail 4 has been placed so that the outer flange 6 fits snugly within the recess 5, and comes in contact with the flange 7, a tapering dove-tail shaped wedge 8 is driven 60 into tapering dove-tail grooves 9 and 10. This tapering dove-tail shaped wedge 8 is provided with an inturned flange 11 which comes in contact with the upper surface of the inner flange 12 of the rail 4, thereby 65 securing the rail 4 to the tie member 1.

By referring to Figure 2 it will be seen that I have provided means for fastening securely the ends 13 and 14 of rails 15 and 16. This is done by providing an upturned 70 fish bar or plate 17 formed out of the material taken from the opening 2. This fish bar or plate 17 is provided with a bond housing 18, which is more clearly shown in Figure 3. The outer flanges 19 and 20 of the rails 75 15 and 16 are secured within a recess 21 formed at the base of the fish bar or plate 17. This fish bar or plate 17 is also provided with a tongue 22 which is bent inwardly into a recess 23 formed in the neck 24 of the rail 16. The object of this tongue 22 is to keep the ends 13 and 14 of the rails 80 15 and 16 in a desired relation to each other. The rails 15 and 16 are held in close contact with the fish bar or plate 17 by means 85 of a tapering dove-tail shaped wedge 25 fitting in tapering dove-tail grooves 26 and 27. This tapering dove-tail shaped wedge 25 is provided with an inturned and upwardly 90 extending portion 28 which forms a fish plate and a securing means for the inner flange 29 of the rails 15 and 16.

It is obvious that such changes in the size, proportion and minor details of construction as are permissible by the appended 95 claim, may be resorted to without departing from the spirit and scope of the invention.

What I claim is:

In a device of the class described, a 100 pressed metallic body portion, a fish bar or plate formed by an upturned portion formed by turning up a portion of the top of said pressed metallic body portion, a tongue

formed on said fish plate or bar for the purpose of functioning with a recess formed in a neck of a rail, a tapering dove-tail shaped wedge, an inturned and upturned portion formed on said wedge for the purpose of forming a close contact with an inner flange of a rail and the neck of said rail,

substantially as described for the purpose set forth.

In testimony whereof I affix my signature.

ALBERT H. DAVIS.
